CLAIM

The ornamental design for multiple stroke ratchet tool for crimping, cutting or the like, as shown and described.

DESCRIPTION

FIG. 1 is a perspective view of the multiple stroke ratchet tool for crimping, cutting or the like showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof.

FIG. 6

FIG. 4

FIG. 3

FIG. 5

FIG. 7
